UNITED STATES PATENT OFFICE.

HERBERT R. KEITHLEY, OF BUFFALO, NEW YORK.

RAILWAY-CAR TRUCK.

SPECIFICATION forming part of Letters Patent No. 702,565, dated June 17, 1902.

Application filed April 11, 1902. Serial No. 102,437. (No model.)

To all whom it may concern:

Be it known that I, HERBERT R. KEITHLEY, a citizen of the United States, residing at Buffalo, in the county of Erie and State of New York, have invented new and useful Improvements in Railway-Car Trucks, of which the following is a specification.

This invention relates to a truck for railway-cars which is built up of commercial rolled shapes and plates.

In my application of United States Letters Patent, Serial No. 90,470, filed January 20, 1902, is disclosed a truck which comprises, briefly stated, a transverse transom and two trussed side frames secured to opposite ends of the transom, each consisting of two pedestals supported from the axle-boxes by springs and tension and compression chords formed of Z-bars arranged with their webs vertical and secured at their ends to the upper ends of the pedestals, the truck embodying, as fully described in said application, the essential and distinctive features of the well-known "diamond" and "pedestal" types of trucks. The present invention is directed to a truck of the same general type.

The primary object of the invention is to produce a built-up truck-frame of this general type which is simple in construction, is composed of the minimum number of parts, and which has the maximum strength and rigidity to sustain loads and resist the shocks and strains to which railway-car trucks are subjected.

In the accompanying drawings, consisting of two sheets, Figure 1 is a side elevation of a railway-car truck embodying the invention. Fig. 2 is an end view showing one half of the truck-frame in elevation and the other half in section, the plane of the sectional portion being in line 22, Fig. 1. Fig. 3 is a plan view of the truck.

Like letters of reference refer to like parts in the several figures.

The truck-frame comprises two side trussed frames connected by a transverse transom, each of the side frames being composed of pedestals at or near the ends of the truck, and connecting chord members.

A represent the pedestals, which are preferably, as shown in the drawings, of inverted-U shape and formed of angle-bars arranged

with one flange *a* standing vertically and the other flange *a'* projecting outwardly from the inner edge of the vertical flange. The pedestals straddle the journal-boxes B, as usual, being supported therefrom by springs B', and are guided by the journal-boxes in the up-and-down movements of the truck-frames.

C and D represent, respectively, the lower and upper or tension and compression chords of the trussed side frames. The tension-chord is bent to provide horizontal end portions *c*, which extend over and rest upon the upper horizontal portions of the outwardly-projecting flanges *a'* of the pedestals, downwardly-converging inclined portions and a central horizontal portion *c'* connecting the lower ends of the inclined portions. The upper or compression chord is provided with end portions *d*, which rest upon the end portions of the tension-chord, and is preferably bent to provide a central horizontal portion *d'* and inclined intermediate portions connecting the central and end horizontal portions. The tension and compression chords are separated at their middle portions by an intervening space for the reception of the ends of the transverse transom. The tension and compression chords are formed of Z-bars arranged with their webs standing vertically in substantially the same vertical plane and their flanges projecting horizontally in reverse arrangement—that is to say, the upper flange *c*² of the tension-chord and the lower flange *d*² of the compression-chord extend in the same direction from the webs and are superposed, and the lower flanges *c*³ of the tension-chord and the upper flanges *d*³ of the compression-chord extend in the same direction, one above the other. The end horizontal portions of the lower flange of the compression-chord rest directly upon and are secured to the end horizontal portions of the upper flange of the tension-chord by rivets *e*, and, if necessary, the connection may be strengthened by vertical plates, (shown at F,) which are arranged beside the end portions of the webs of the tension and compression chords between the separated flanges and secured to the webs of both chords by rivets *f*. The rivets connecting the plates to the lower chord also secure the latter to the vertical flanges of the pedestals. In the construction shown in the drawings the

lateral flanges of the pedestals and the separated flanges of the chords project outwardly from their webs; but obviously the parts can be reversed so that the said flanges will extend inwardly.

5 G represents a horizontal frame member which connects the lower ends of the two pedestals. This member is preferably in the form of an angle bar or plate, with a lower inwardly-projecting flange g , and its ends, which stand vertically beside the inner faces of the vertical flanges of the pedestals, are secured thereto by rivets g' passing through the pedestal flanges and the bar or plate. The vertical web of this plate or bar stands against the inner face of the central horizontal portion c' of the tension-chord beneath the inwardly-projecting flange thereof.

H represents tie-bolts connecting the legs 20 of the pedestals beneath the journal-boxes. The bolts pass through the lateral flanges of the pedestals and through spacing-sleeves h . A tie of any other desired form may be employed.

25 The transom shown in the drawings for connecting the side frames is preferably composed of two separated channel-beams J, the upper and lower inwardly-projecting horizontal flanges of which are respectively connected 30 by an upper plate j , riveted to the upper flanges, and a lower plate j' , riveted to the lower flanges. The plates may be in the form of cover-plates or short plates at the ends of the transom. The transom extends at each 35 end through the space between the tension and compression chords of the adjacent side frame and is connected at its top to the lower flange of the compression-chord by rivets j^2 and at its bottom to the upper flange of the 40 tension-chord by rivets j^3 . The connection of each end of the transom with the side frame is reinforced and strengthened by an angle-bar K, which is bent in U form around the top and sides of the end of the transom 45 and has its vertical flange connected to the webs of the tension and compression chords by rivets k and k' , respectively, and its horizontal flange connected to the top and sides of the transom by rivets k^2 .

50 The described construction of the side frames gives great strength throughout, and especially at the ends of the frames, for supporting loads, and great lateral strength and stiffness to resist the side thrusts to which 55 truck-frames are subjected in rounding curves. The side thrust of the transom is principally resisted by the rivets connecting the transom with the horizontal flanges of the side-frame chords and the reinforcing an-

60 gle-bars K.

The truck-frame is built of very few parts and the joints between these parts are so arranged that large riveting area is secured.

I claim as my invention—

65 1. In a trussed side frame for railway-car trucks, the combination of two pedestals, a tension-chord connected to said pedestals and

formed with a vertical web and a horizontal flange, and a compression-chord formed with a vertical web and a horizontal flange, the end 70 portions of the webs of said tension and compression chords being arranged in substantially the same plane, and the end portions of the horizontal flange of one member being arranged directly above and riveted to the end 75 portions of the horizontal flange of the other chord, substantially as set forth.

2. In a trussed side frame for railway-car trucks, the combination of pedestals each having a vertical web and a laterally-projecting 80 flange, a tension-chord formed with a vertical web and a horizontal flange the end portions of the web being connected to the webs of said pedestals, and a compression-chord formed with a vertical web and a horizontal 85 flange, the end portions of the web of said compression-chord being arranged in substantially the same vertical plane and above the end portions of the web of the tension-chord, and the end portions of the horizontal flange 90 of the compression-chord resting on and riveted to the end portions of the flange of the tension-chord, substantially as set forth.

3. In a trussed side frame for railway-car trucks, the combination of two pedestals, a 95 tension-chord connected to said pedestals and formed with a vertical web and a horizontal flange, a compression-chord formed with a vertical web and a horizontal flange, the end 100 portions of the webs of said tension and compression chords being arranged in substantially the same plane, and the end portions of the horizontal flange of one member being arranged directly above and riveted to the end portions of the horizontal flange of the 105 other chord, and vertical plates arranged beside and secured to the end portions of the webs of said chords, substantially as set forth.

4. In a trussed side frame for railway-car trucks, the combination of pedestals each having a vertical web and a laterally-projecting flange, a tension-chord formed with a vertical web and a horizontal flange the end portions of the web being connected to the webs of said 110 pedestals, a compression-chord formed with a vertical web and a horizontal flange, the end 115 portions of the web of said compression-chord being arranged in substantially the same vertical plane and above the end portions of the web of the tension-chord, and the end portions of the horizontal flange of the compression-chord resting on and riveted to the end 120 portions of the flange of the tension-chord, and vertical plates arranged beside and secured to the end portions of the webs of said 125 chords, substantially as set forth.

5. In a trussed side frame for railway-car trucks, the combination of two pedestals, a tension-chord in the form of a Z-bar connected to said pedestals and arranged with its web 130 vertical, a compression-chord in the form of a Z-bar arranged with its web vertical, the end portions of the web of the compression-chord being arranged in substantially the

same vertical plane and above the end portions of the web of the tension-chord, and the end portions of the lower horizontal flange of the compression-chord resting upon the end

5 portions of the upper horizontal flange of the tension-chord, and vertical plates arranged beside and secured to the end portions of the webs of said chords between the separated flanges thereof, substantially as set forth.

10 6. The combination of two side frames, the chords of each of which are formed with a vertical web and a horizontal flange, a transom the ends of which project between the chords of said side frames, and bars each having a vertical web secured to the webs of the chords of the adjacent side frame and a flange secured to the adjacent end of the transom, substantially as set forth.

15 7. The combination of two trussed side frames, the chords of each of which are formed with a vertical web, and a horizontal flange, a transom composed of channel-beams the ends of which project between the chords of

said side frames, and bars each having a vertical web secured to the webs of the chords 25 of the adjacent side frame and a flange secured to the adjacent ends of the transom, substantially as set forth.

8. The combination of two trussed side frames, the chords of each of which are formed 30 with a vertical web and a horizontal flange, a transom composed of channel-beams the ends of which project between the chords of said side frames, plates connected to the upper and lower flanges of the transom-channels 35 and to the chords of the side frames, and bars each having a vertical web secured to the webs of the chords of the adjacent side frame and a flange secured to the adjacent ends of the transom, substantially as set forth. 40

Witness my hand this 4th day of April, 1902.
